UNITED STATES PATENT OFFICE.

JOHN A. NORDLOH, OF CINCINNATI, OHIO.

SHOE.

1,213,123.

Specification of Letters Patent. Patented Jan. 16, 1917.

Application filed February 25, 1916. Serial No. 80,439.

To all whom it may concern:

Be it known that I, JOHN A. NORDLOH, a citizen of the United States, residing at Evanston, Cincinnati, in the county of 5 Hamilton and State of Ohio, have invented certain new and useful Improvements in Shoes, of which the following is a specification.

This invention relates to improvements in 10 shoes and more particularly to soft sole shoes. Shoes of this type now on the market have the upper united to the sole by a seam running entirely around the inside of the shoe at the margin of the sole and ordinarily this seam is not covered in any way whatsoever and proves decidedly uncomfortable particularly to the heel. Furthermore, such shoes are also uncomfortable to 15 wear due to the absence of a counter, no satisfactory means, so far as I am aware, having been previously discovered whereby a counter could be conveniently inserted in a shoe of this type. The present invention, therefore, aims to provide a shoe of this 20 type having a counter so inserted as to cover the seam above referred to at the heel of the shoe and thereby render the shoe more comfortable to wear and also prevent sagging or collapse of the heel.

25 In the accompanying drawings: Figure 1 is a fragmentary sectional perspective view of the heel portion of a shoe of the type above mentioned formed in accordance with the present invention. Fig. 2 is a vertical transverse sectional view through the heel portion of the shoe. Fig. 3 is a view similar to Fig. 1, illustrating a slight modification of the invention. Fig. 4 is a view 30 similar to Fig. 2 illustrating the structure shown in Fig. 3.

In the drawings the numeral 1 indicates the heel portion of the upper of the shoe and 2 the sole of the shoe. The upper 1 may be of leather, cloth, or, in fact, any 35 other suitable flexible material, and the sole 2 is preferably of thin flexible leather, although it also may be of other material if found desirable. The lower edge of the upper 1 is united to the margin of the sole 2 by a line of stitching forming a seam 3, the edges of which seam are located within the shoe so that exteriorly the shoe will present a neat and uniform appearance at the line of juncture of the upper and sole.

40 The shoe embodying the present invention also includes an insole which is indi-

cated by the numeral 4 and which is preferably substantially of the same marginal contour as the sole 2.

The heel of the shoe shown in Fig. 1 of 60 the drawings is stiffened and supported by a counter indicated in general by the numeral 5 and this counter may be secured within the heel portion of the upper 1 by leather cement or by means of lines of stitching as 65 illustrated in the drawings.

In that form of the invention shown in 70 Figs. 1 and 2 of the drawings, the lower edge or marginal portion of the counter 5 is provided at its rear portion with a number of V-shaped incisions 6 and the said portion of the counter is turned inwardly before the insole is inserted so that after the insole has been placed within the shoe and is stitched or otherwise secured in place, 75 the said inturned edge portion of the counter blank, which is indicated by the numeral 7, will extend between the marginal portion of the insole and the marginal portion of the sole 2, as clearly shown in the said figures 80 of the drawings. The V-shaped incisions 6, of course, permit of the said inturned marginal portion of the counter being received between the sole 2 and insole 4 without causing any bulging in either sole. In order 85 that the space defined by the edge of the inturned marginal portion of the counter may be filled so that the insole 4 will not sag into this space, a filler blank 8 is interposed between the two soles. By reference to the said Figs. 1 and 2 of the drawings 90 it will be observed that the counter 5 serves to completely cover the seam 3 at the heel portion of the shoe so that this seam will not come in contact with the heel of 95 the wearer of the shoe and render the shoe uncomfortable. At the same time the counter serves to stiffen the heel portion of the upper and prevent sagging or collapse of the same.

100 In that form of the invention shown in Figs. 3 and 4 of the drawings, the upper, sole and insole are indicated by the same reference numerals as in Figs. 1 and 2 but in this form of the invention the counter, 105 which is indicated by the numeral 9, does not have its lower marginal portion turned in to lie between the two soles, but on the other hand, its lower edge terminates at the seam 3. The counter in this form of 110 the invention, however, is provided with a lining which is indicated by the numeral 10

and which is preferably of substantially the same shape or marginal outlines as the said counter and may be of thin leather or any other suitable material and this lining 5 has its lower marginal portion provided with two or any desired number of V-shaped incisions as in the case of the marginal portion of the counter 5 in Figs. 1 and 2 of the drawings and turned in to lie between 10 the soles 2 and 4. In this form of the invention the counter 9 serves to stiffen the heel portion of the upper and prevent its collapse and the lining 10 serves not only to render the shoe more comfortable as it prevents direct contact with the counter, but 15 also serves to cover the seam 3 in the same manner as does the counter 5 in the previously described form of the invention.

It will be understood that in one sense 20 of the word the lining 10 constitutes a stiffening element for the heel and that, there-

fore, of both forms of the invention herein illustrated and described it may be said that the heel portion of the upper of the shoe is provided interiorly with a stiffening 25 element having its lower marginal portion turned in to lie between the sole and insole of the shoe so as to cover the seam uniting the upper to the sole.

Having thus described the invention, 30 what is claimed as new is:

A shoe comprising an upper, a sole united to the upper by a seam extending along the margin of the sole, an insole, and a member fitted within the heel portion of the said 35 upper and constituting a means for stiffening the heel portion of the upper and having its lower marginal portion turned in to lie between the said sole and insole in position covering the said seam. 40

In testimony whereof I affix my signature.
JOHN A. NORDLOH. [L.S.]
